UNITED STATES PATENT OFFICE.

BENNO VOM EIGEN, OF NEWARK, NEW JERSEY, ASSIGNOR TO AUGUST GOERTZ & CO., A CORPORATION OF NEW JERSEY.

BAG-FRAME AND HINGE MEMBER THEREFOR.

1,262,288.

Specification of Letters Patent. Patented Apr. 9, 1918.

Application filed June 30, 1917. Serial No. 178,013.

To all whom it may concern:

Be it known that I, BENNO VOM EIGEN, a citizen of the United States, residing at Newark, in the county of Essex and State 5 of New Jersey, have invented certain new and useful Improvements in Bag-Frames and Hinge Members Therefor; and I do hereby declare the following to be a full, clear, and exact description of the invention, 10 such as will enable others skilled in the art to which it appertains to make and use the same, reference being had to the accompanying drawings, and to characters of reference marked thereon, which form a part of this 15 specification.

The present invention has reference, generally, to improvements in hinges for bag-frames; and the invention relates, more particularly, to a novel construction of hinge 20 devices provided with a novel arrangement of spring tension means for retaining the hinge members in their open position.

The invention has for its principal object to provide a simple, strong and cheap construction of hinge device for pivotally connecting together the members or sections of a bag-frame, or the like; the same providing, from the standpoint of manufacturing, a very easily assembled hinge construction 30 durably connected with the frame members or sections, and provided with an easily assembled spring means adapted to so co-operate with the hinge devices as to easily hold the same, and consequently the frame 35 members or sections, in open positions; and the same providing, from the structural standpoint, a hinge device comprising a minimum number of parts provided with means for quickly and strongly connecting 40 the same in operative relation to the frame members or sections, and further provided with a spring means rigidly anchored in proper operative relation to the hinge devices, and yet free to exercise its tension 45 directly and forcefully upon the hinge devices to hold the same, and the frame members or sections which they serve to pivotally unite, in open relation.

Other objects of the present invention, not 50 at this time more particularly enumerated, will be clearly understood from the following detail description of the same.

With the various objects of my present invention in view, the same consists, primarily, in the novel construction of hinge devices

for bag frames, and the like, hereinafter set forth, and the invention consists furthermore, in the novel arrangements and combinations of the several devices and parts, as well as in the details of the construction of 60 said parts, all of which will be more fully described in the following specification, and then finally embodied in the appended claims.

The invention is fully illustrated in the 65 accompanying drawings, in which:—

Figure 1 is a side elevation of a bag-frame equipped with the novel construction of hinge devices made according to and embodying the principles of my present in- 70 vention.

Fig. 2 is an enlarged detail side view of the hinge-devices in assembled relation to the bag-frame sections, the said hinge-devices being shown in closed position; Fig. 3 75 is a similar view showing the hinge devices in open position; Fig. 4 is a vertical longitudinal section through the hinge devices while in closed position; and Fig. 5 is a similar section of the hinge devices in open posi- 80 tion.

Fig. 6 is a plan view of a blank from which one of the members of the hinge device is formed; and Fig. 7 is a similar plan view of the other member of the hinge de- 85 vice.

Fig. 8 is a composite plan view of the members of the hinge device, together with the pintle therefor, after the same are formed ready to be assembled and connected with 90 the bag-frame sections.

Fig. 9 is a plan view of the spring member adapted to be employed with the hinge-device; and Fig. 10 is a side edge view of the same. 95

Similar characters of reference are employed in all of the hereinabove described views, to indicate corresponding parts.

Referring now to the said drawings, the reference character 1 indicates the outer 100 frame section and 2 the inner frame section, the former having the usual side portion or flange 3, and the latter the usual side portion or flange 4.

The novel hinge device comprises a hinge 105 member 5 and a hinge member 6. The said hinge member 5 consists of a main body or box, extending from the side flanges 7 of which, in properly spaced or distanced relation, are clenching lugs 8 for securing the 110

same to the flange 3 of the frame section 1. Integrally formed with the inner end of said hinge member 5 is an outwardly extending tongue 9 (see Fig. 6) from which 5 a pintle bearing 9' is formed by bending the same outwardly and around, and then doubling back the free end 9" upon the inside face of said hinge member 5, and finally securing said free end 9" to the 10 hinge-member 5 by a rivet 10, or other convenient form of fastening means. In forming said pintle-bearing 9', the body of the same is bent or bowed outwardly at the rear side of its circumferential surface to 15 provide a nosing 11. The said hinge member 6 also consists of a main body or box, extending from the side flanges 12 of which, in properly spaced or distanced relation, are clenching lugs 13 for securing the same 20 to the flange 4 of the inner frame section 2. Integrally formed in connection with the inner end of said hinge member 6 are pintle supporting means. These pintle supporting means comprise laterally extending carrier 25 arms 14 integrally connected with the marginal edges of the side flanges 12, and having outwardly or longitudinally extending portions 15 projecting beyond the inner end of said hinge member 6, and integrally connected with said portions 15, in outward lateral extension therefrom, are the perforated pintle supporting ears 16 (for all of which see Fig. 7 of the drawings). In 30 stamping up the blank from which said hinge member 6 is formed after the side flanges 12 are formed, the said carrier arms 14 and their portions 15, are doubled back over the outer surface of the flanges 12, which operation positions the supporting 35 ears 16 in proper pintle receiving position, and spaced laterally apart sufficiently to permit the pintle bearing 9' of the hinge member 5 to be inserted therebetween.

The reference character 17 indicates a 45 pintle, the same being provided with end extensions 18 of reduced diameter so as to provide shoulders 19 adjacent the ends of said pintle thus formed. When the hinge members 5 and 6 are assembled together in 50 mutually co-operative relation, the opposite end extensions 18 are respectively received through the perforations of the pintle supporting ears 16, and the outwardly projecting ends are riveted over (as at 20) to 55 rigidly secure the pintle in proper lateral extension between said ears, and properly inserted through the pintle bearing 9' of the hinge member 5. When so assembled the ears 16 are respectively forced against the 60 shoulders 19 of the pintle, and thereby retained in properly spaced relation against undue frictional binding upon the ends of the pintle bearing 9', thus assuring a free and non-binding pivotal connection between 65 the respective hinge members 5 and 6. Each

side flange 12 of the hinge member 6 is provided in its marginal edge with an indentation or notch 21 of a depth equal to the thickness of the body of a leaf spring described below, said indentations or notches 70 being laterally opposite and preferably located between the pairs of clenching lugs 13 with which said side flanges 12 are provided. The reference character 22 indicates the main body of a leaf spring adapted for 75 use in connection with said hinge device. Extending from the sides of said leaf spring 22, in opposite location, are lugs or tongues 23 which, when the spring is associated with the hinge device, are receivable in the said 80 indentations or notches 21 provided in the flanges 12 of said hinge member 6. Said spring 22 is provided at its free end with a downwardly inclined holding finger or lip 24, the purpose of which will presently appear.

In assembling or securing the hinge device in operative relation to the sections of the bag-frame, the hinge member 5 is registered against one end of the flange 3 of the 90 frame-section 1 so that its clenching lugs 7 straddle the same in position to be turned over the marginal edges of said flange 3. Preferably the said marginal edges of said flange 3 are indented to receive said clenching lugs 7, so that the hinge member 5 is not only secured firmly to the frame section, but also maintained against longitudinal displacement thereon. The hinge member 95 6 is secured to the side flange 4 of the frame 100 section 2, in a similar manner, by means of its clenching lugs 13. Before the hinge member 6 is assembled with said frame section 2, however, the spring 22 is operatively associated therewith by inserting the 105 tongues 23 in the notches 21 of the flanges 12, thus properly positioning said spring and holding the same not only against longitudinal displacement from said hinge-member 6, but also spaced away from the inner 110 surface of the latter so that its free end will be capable of a proper play or movement when exercising its functions. When the spring is thus properly secured and positioned its holding finger or lip 24 rides upon the circumferential surface of said pintle bearing 9' (as shown more clearly in Fig. 4 of the drawings); when the bag-frame sections are moved on their hinge connection to open position, the nosing 11 formed upon or projecting from the pintle bearing 9' is moved beneath said holding finger or lip 24, the spring lifting or flexing to permit the said finger or lip 24 to ride over the same, and then finally engage said nosing 11 in holding relation thereto (as shown more clearly in Fig. 5 of the drawings), thus operating to hold the bag-frame sections open and against tendency to move into closed position, until enough pressure 125 130

is applied thereto to overcome the tension of the said spring 22.

I am aware that some changes may be made in the several combinations and arrangements of the various parts, as well as in the details of the construction of said parts, without departing from the scope of the present invention. Hence, I do not limit my invention to the exact details above described and as shown in the accompanying drawings, except as the same may be limited by the scope of the claims hereto appended.

I claim:—

1. In a device of the kind described a pair of hinge members for respective attachment to the sections of a bag-frame, one of said hinge members having carrier arms doubled laterally back over its sides adjacent to its abutting end, a portion of said carrier arms having pintle supporting ears projecting outwardly therefrom, a pintle having reduced extensions at each end for insertion through said pintle supporting ears, the projecting ends of said extensions being riveted down upon the exterior surface of said ears, the other of said hinge members having a tongue at its abutting end doubled around to provide a pintle bearing surrounding said pintle, the free end of said tongue being riveted to the body of said second hinge member, a nosing pressed outwardly from the circumferential surface of said pintle bearing, and a spring member secured to said first mentioned hinge member having a holding lip at its free end adapted to coöperate with said nosing to hold said hinge members in open position.

2. A hinge device comprising a hinge member having side flanges, clenching lugs projecting from said side flanges, carrier arms integrally connected with said side flanges at the abutting end of said hinge member, said carrier arms being doubled outwardly and backwardly against the exterior surface of said side flanges, said carrier arms having portions extending beyond the ends of said side flanges provided with upwardly projecting pintle supporting ears, a pintle having reduced extensions at each end for insertion through said pintle supporting ears, the projecting ends of said extensions being riveted down upon the exterior surface of said ears, a second hinge member having side flanges, clenching lugs projecting from said side flanges, a tongue extending outwardly from the abutting end of said second hinge member, said tongue being bent outwardly and around to provide a pintle bearing engaged over said pintle, the free end of said tongue being extended beneath said second hinge member and riveted to its body, a nosing pressed outwardly from the under side of said pintle bearing, and a spring member secured to said first mentioned hinge member having a holding lip

at its free end adapted to coöperate with said nosing to hold said hinge members in open position.

3. A hinge device comprising a hinge member having side flanges, clenching lugs projecting from said side flanges, carrier arms integrally connected with said side flanges at the abutting end of said hinge member, said carrier arms being doubled outwardly and backwardly against the exterior surface of said side flanges, said carrier arms having portions extending beyond the ends of said side flanges provided with upwardly projecting pintle supporting ears, a pintle having reduced extensions at each end for insertion through said pintle supporting ears, the projecting ends of said extensions being riveted down upon the exterior surface of said ears, a second hinge member having side flanges, clenching lugs projecting from said side flanges, a tongue extending outwardly from the abutting end of said second hinge member, said tongue being bent outwardly and around to provide a pintle bearing engaged over said pintle, the free end of said tongue being extended beneath said second hinge member and riveted to its body, a nosing pressed outwardly from the under side of said pintle bearing, a leaf spring, transversely extending lugs at the opposite sides of said spring, the side flanges of said first mentioned hinge member having indentations in their marginal edges to receive said lugs to hold the spring against longitudinal displacement and spaced away from the body of said hinge member, and the free end of said spring having a downwardly inclined holding lip registering over said pintle bearing and adapted to engage said nosing to hold said hinge members in open position.

4. A hinge device comprising a hinge member having side flanges, carrier arms integrally connected with said side flanges at the abutting end of said hinge member, said carrier arms being doubled outwardly and backwardly against the exterior surface of said side flanges, said carrier arms having portions extending beyond the ends of said side flanges provided with upwardly projecting pintle supporting ears, a pintle having reduced extensions at each end for insertion through said pintle supporting ears, the projecting ends of said extensions being riveted down upon the exterior surface of said ears, a second hinge member having side flanges, and a pintle engaging knuckle at the abutting end of said second hinge member.

5. A hinge device comprising a hinge member having side flanges, carrier arms integrally connected with said side flanges at the abutting end of said hinge member, said carrier arms being doubled outwardly and backwardly against the exterior surface of said side flanges, said carrier arms hav-

ing portions extending beyond the ends of said side flanges provided with upwardly projecting pintle supporting ears, a pintle having reduced extensions at each end for insertion through said pintle supporting ears, the projecting ends of said extensions being riveted down upon the exterior surface of said ears, a second hinge member having side flanges, a pintle engaging knuckle at the abutting end of said second hinge-member, a nosing formed on the exterior surface of said pintle engaging knuckle, a leaf spring, transversely extending lugs at the opposite sides of said spring, the side flanges of said first mentioned hinge member having indentations in their marginal edges to receive said lugs to hold said spring against longitudinal displacement and spaced away from the body of said hinge member, and the free end of said spring having a downwardly inclined holding lip adapted to engage said nosing to hold said hinge members in open position.

6. A hinge device comprising a hinge member having side flanges, a tongue extending outwardly from the abutting end of said hinge-member, said tongue being bent outwardly and around to provide a pintle bearing, the free end of said tongue being

extended beneath the body of said hinge member between its side flanges riveted to said body, a second hinge member having side flanges, pintle supporting means connected with said side flanges at the abutting end of said hinge member, a pintle supported by said means over which said pintle bearing is engaged, and a nosing pressed outwardly from the under side of said pintle bearing, a leaf spring, transversely extending lugs at the opposite sides of said spring, the side flanges of said second hinge member having indentations in their marginal edges to receive said lugs to hold the spring against longitudinal displacement and spaced away from the body of said hinge member, and the free end of said spring having a downwardly inclined holding lip registering over said pintle bearing and adapted to engage said nosing to hold said hinge members in open position.

In testimony, that I claim the invention set forth above I have hereunto set my hand this 27th day of June, 1917.

BENNO VOM EIGEN.
